A. KESTENMAN.
LINGERIE CLASP.
APPLICATION FILED AUG. 5, 1918.

1,327,761.

Patented Jan. 13, 1920.

UNITED STATES PATENT OFFICE.

ABRAHAM KESTENMAN, OF PROVIDENCE, RHODE ISLAND, ASSIGNOR TO KESTENMAN BROS. MFG. COMPANY, OF PROVIDENCE, RHODE ISLAND, A FIRM COMPOSED OF ABRAHAM KESTENMAN AND CHARLES H. KESTENMAN.

LINGERIE-CLASP.

1,327,761.

Specification of Letters Patent. Patented Jan. 13, 1920.

Application filed August 5, 1918. Serial No. 248,244.

To all whom it may concern:

Be it known that I, ABRAHAM KESTENMAN, a citizen of the United States, residing at Providence, in the county of Providence, 5 State of Rhode Island, have invented certain new and useful Improvements in Lingerie-Clasps, of which the following is a specification.

My invention is an improved lingerie-clasp for the shoulder-straps of ladies' 10 undergarments. The object of my improvement is to provide a simplified device of this kind which is easier and cheaper to manufacture than the usual type, and neater 15 and more ornamental in appearance, besides being more durable in use.

The manner and means for carrying out the improvement are fully described in the 20 following specification, illustrated by the accompanying drawings, in which like reference characters designate like parts. In the drawings:—

Figure 1 is a plan view of my improved lingerie-clasp showing its two parts or jaw-members closed together;

Fig. 2, a side elevation showing the jaw-members in closed relation and illustrating the open position of the upper jaw in dotted lines;

Fig. 3, an enlarged, plan view of a portion of the jaw-hinge;

Fig. 4, an enlarged, side elevation of the hinge-portion of the clasp; and

Fig. 5, an enlarged, plan view of the strip 35 or blank from which the lower jaw-member is constructed.

Referring to the drawings, my improved clasp C comprises two opposite jaw-members 2 and 3 which are hinged together at one 40 end and provided with means for clasping their opposite ends in closed relation to confine the shoulder-straps of the garment therebetween. As shown particularly in Fig. 2, the lower jaw-member 3 comprises a flat 45 base-piece 4, which is arched upwardly slightly between its ends, and provided with an upper, bowed bridge-piece 5 overlying the full length of its top. The lower jaw 3 of the clasp is constructed in one piece from

a relatively thin strip or blank B of sheet-metal of the form shown in Fig. 5. As here illustrated the lower base-piece 4 of the jaw-member is of uniform width throughout its length with a longitudinal slot 6 cut into its end for a purpose as later explained. At 55 the opposite end of the base-piece 4 the strip is cut away along its sides to form a relatively narrow bar which, when bent or folded to overlie the base 4, provides the arched bridge-piece 5. Adjacent the outer 60 end of the narrowed bridge-piece 5 the strip is left of the same width as the main base-piece 4, forming a lateral bar or cross-member 7. Beyond the cross-bar 7 the strip extends in a narrowed tongue 8 which forms 65 a part of the hinge-joint for the two parts of the clasp.

In bending up the lower jaw-member 3 the base-piece 4 is curled around at the point X—X, shown in Fig. 5, to form a circular loop 9 at its end, see Fig. 2. From this point the narrow bar 5 is arched upwardly above the top of the base 4 to overlie the latter and provide a longitudinal bridge-piece which acts to clamp the garment-straps against the upper jaw 2 when the latter is clasped to the lower jaw 3, as shown in Fig. 2.

The upper jaw 2 consists of a thin strip of metal of the same width as that of the 80 base-piece 4, bent into arcuate shape between its ends to conform to the general, curved shape of the whole clasp. At one end it is formed with two spaced-apart ears curled around into circular loops 10, 10, see 85 Figs. 1 and 2, which are adapted to receive a lateral hinge-pin 11. To unite the hinge-parts with the lower jaw-member 3 the tongue 8 at the end of the bridge-piece 5 is curled around the hinge-pin 11, as shown 90 in Fig. 4, between the two ears 10, 10, see also Fig. 1. Usually the pin 11 is swaged over at its ends to hold it in place, and is fast in the ears 10, 10, but free to turn in the loop of the tongue 8.

It has already been explained that the end of the base-piece 4 which underlies the hinge-portion of the clasp C is slotted at 6,

see Fig. 5, and the purpose of this is to provide two spaced-apart lugs 12, 12 which are employed as a reinforcement for the hinge-joint. As shown most clearly in Fig. 5, these lugs 12, 12 are bent upwardly adjacent the cross-bar 7 on the bridge-piece 5, with their sides straddling the tongue 8. The ends of the lugs 12, 12 project above the bridge-piece 5 and are bent into arcuate 10 shape to overlie the ears 10, 10 which form the hinge-connection of the upper jaw-member 2. Through this construction the lower base-piece 4 of the jaw 3 is rigidly connected with the end of the bridge-piece 5 15 and also with the hinge-joint of which it forms a part. The prime purpose of this connection is to reinforce and stiffen the hinge-joint to prevent undue play or looseness of the jaws of the clasp. The projections or lugs 12, 12 fit snugly against the hinge-ears 10, 10 and through their inherent 20 spring tendency hold the parts of the hinge from side play or twisting, thus preventing a shakily joint. Furthermore, the spring pressure of the lugs 12, 12 against the hinge-ears 10, 10 causes a slight frictional 25 resistance to the movement of the parts of the hinge, and this has a tendency to make for a smoother operation of the jaw-members; while also providing for holding the 30 clasp in open relation when it is to be applied to the garments. At the outer end of the upper jaw 2, opposite from the hinge-joint, is a curved hook 13 which is adapted 35 to be snapped down over the circular loop 9 on the lower jaw 3 to hold the parts of the clasp in closed relation as illustrated in Fig. 2. The upper jaw 2 may be swung 40 open to the position shown in dotted lines in Fig. 2, or even farther back if desired, and after the shoulder-straps of the garment have been entered between its parts the jaw 3 is closed toward the lower jaw 3 and its hook 13 snapped over the loop 9. With 45 the parts of the clasp in closed relation the fabric-straps of the garments are bound 50 snugly in place against the spring bridge-piece 5, and this prevents the clasp from slipping out of place or sliding along the straps.

As will be observed from the foregoing description, my improved lingerie-clasp is similar in principle to like devices now known in the art. The improvement in the 55 invention resides, however, in the novel construction and method of operation of the hinge-joint. As before explained, the lower jaw-member 3 is formed in one piece with the ends of the base 4 and bridge 5 united 60 by an ingenious arrangement which also provides the reinforcement for the hinge-joint of the upper jaw 2. This reinforcement not only serves to prevent side play at the joint but also tends to hold the two jaws

properly alined and positioned to provide 65 for the coöperation of their clasping ends. That is to say, the hinge is prevented from becoming loose or shakily so that the outer ends of the jaws will always clasp snugly and securely. For this reason my improved 70 clasp is easier to operate and much more durable in use than most devices of this type. At the same time it can be manufactured more easily and economically, since the parts do not require to be united with 75 solder, and it is also neater and more ornamental in appearance.

Slight modifications might be made in the form and structure of the parts of my improved device without departing from the 80 spirit or scope of the invention; therefore, without limiting myself to the exact embodiment shown, what I claim is:—

1. In a lingerie-clasp for ladies' garments, the combination of two opposite jaw-members hinged together at one end, with the outer free end of the upper member formed with a hook adapted to snap over a circular loop on the corresponding end of the lower member, said loop being extended inwardly 90 toward the hinge in a bowed spring formed integral with and overlying the lower member and united thereto at its opposite end by spaced-apart lugs on one part engaging the 95 opposite sides of the other part. 95

2. In a lingerie-clasp for ladies' garments, the combination of two opposite jaw-members hinged together at one end, with the outer free end of the upper member formed with a hook adapted to snap over a loop on 100 the corresponding end of the lower member, said loop being extended inwardly toward the hinge in a bowed spring formed integral with and overlying the lower member, the end of said spring opposite from the 105 loop being reduced in width and joined to the lower member by lugs extending up across its opposite sides. 105

3. In a lingerie-clasp for ladies' garments, the combination of two opposite jaw-members hinged together at one end with the outer free end of one member provided with a hook adapted to snap over a loop on the corresponding end of the other member, the hinge-joint being formed by ears on the 115 members constructed in the form of circular loops, a hinge-pin extending through the loops, and lugs of arcuate form on one member arranged to partly surround and bear against the hinge-ears of the other member 120 to reinforce the hinge-joint and prevent side play or looseness thereof. 120

4. In a lingerie-clasp for ladies' garments, the combination of two opposite jaw-members hinged together at one end with the outer free end of the upper member formed with a hook adapted to snap over a loop on 125 the corresponding end of the lower member,

said loop being extended toward the hinge in a bowed bridge-piece formed integral with and overlying the lower member with its end curled around to form one ear of the hinge, 5 the upper member having spaced ears curled around to form the other part of the hinge, a hinge-pin inserted through said ears, and lugs spaced-apart on the lower member extending upwardly to straddle the sides of the bridge-piece with their ends bearing 10 against the hinge-ears on the upper member to reinforce and stiffen the hinge-joint.

In testimony whereof I affix my signature.
ABRAHAM KESTENMAN.
